United States Patent Office.

LUKE L. KELLOGG, OF LEON CENTRE, NEW YORK.

Letters Patent No. 93,537, dated August 10, 1869.

IMPROVEMENT IN PUMPS.

The Schedule referred to in these Letters Patent and making part of the same.

To all whom it may concern:

Be it known that I, LUKE L. KELLOGG, of Leon Centre, in the county of Cattaraugus, and State of New York, have invented a new and improved Force-Pump; and I do hereby declare that the following is a full, clear, and exact description of the construction and operation of the same, reference being had to the accompanying drawings, making a part of this specification, in which the figure is a side elevation and a longitudinal vertical section combined.

This invention relates to a double-acting pump, provided with two buckets moving simultaneously in opposite directions; and

It consists in moving each bucket in one direction through a passage, for the purpose of allowing water to pass through it, and then moving it in exactly the contrary direction through the same passage, for the purpose of forcing the water out of it.

In the drawings—

A is a mass of masonry or other suitable material, in a well or other reservoir of water, and provided with two horizontal passages a, out of each of which opens a vertical passage, a', leading up into the pump-barrel b, to the top of which pump is attached a hose, c.

The pump-handle b' is connected, by rods d, to the upper ends of the elbow-levers e, which are suitably pivoted in the masonry, and the lower ends of which are opposite the mouths of the horizontal passages a.

Two rods h, pivoted at their inner ends to the boxes i, are pivoted at the other ends to the lower extremities of the elbow-levers e.

The boxes i are provided with valves k, opening into the passage.

If force be applied to the handle b' sufficient to work it up and down in the usual manner, at every up-stroke, one box, i, will approach the mouth of the passage a, and water will pass through it into said passage.

At every down-stroke, the valve k closes, and the box i moves toward the vertical passage a', forcing the water along and up through said passage, out at the hose c, or out at the spout e.

The other box i operates at the same time in the opposite direction, moving outward when the first box is moving inward, and *vice versa*, and pouring its stream into the pump-barrel alternately with the first box, so as to keep the barrel always full, and a continuous flow issuing from it.

I do not include the double action of the pump in my claim, as this is effected by a mere duplication of parts.

Having thus described my invention,

What I claim as new, and desire to secure by Letters Patent, is—

The box i, provided with the valve k, in combination with the connecting-rod h, the said box and rod being arranged to operate in a horizontal direction, and with the lever e, connecting-rod d, handle b', pump b, and passages a' a, the latter passage being turned in a horizontal direction so as to receive the box i and rod h, and fit the whole apparatus for use in shallow water, substantially as described.

LUKE L. KELLOGG.
